APPARATUS FOR MOLDING WATER
CLOSET RIMS

James M. Teahen, Detroit, Mich.

Application February 12, 1934, Serial No. 710,923

4 Claims. (Cl. 25—129)

The invention relates to the manufacture of water closet bowls of the type provided with channeled flushing rims. It is the object of the invention, first, to obtain a method of molding a rim separate from the bowl but which is subsequently integrated therewith, said rim having molded-in inclined recesses for forming water discharge ports against the inner face of the bowl. It is a further object to obtain a construction of molding apparatus by which the rim may be formed as described, and which provides further removal of the mold in sections without injury to the molded rim. With these objects in view the invention consists in the construction as herein-after set forth.

In the drawing:

Fig. 1 is a horizontal section through a portion of a water closet bowl showing the rim applied thereto;

Figs. 2 and 3 are respectively a horizontal section on line 2—2 and a vertical section on line 3—3 of Fig. 1;

Fig. 4 is a cross section through the rim forming mold;

Fig. 5 is a similar view showing the mold reversed and with one section removed therefrom;

Fig. 6 is a plan view of the mold showing portions thereof in horizontal section.

As shown in Figs. 1 to 3 inclusive, A is the water closet bowl and B is the hollow rim which is separately cast from the bowl, being provided with a horizontal flange B' overlapping the top of the bowl and integrated therewith along the line B². The rim B is further provided with the downwardly extending portion B³ and the outwardly extending flange B⁴ at its lower end which bears against the inner face of the bowl and is integrated therewith. In the flange B⁴ are formed molded-in inclined recesses D which connect with the channel E within the rim and in connection with the wall of the bowl form downward discharge ports.

The usual method of molding clay for forming ceramic structures is to fill porous plaster molds with fluid clay or what is known as "slip", the water being extracted and absorbed by the pores of the mold, leaving the solid clay in the mold cavity. I employ this general method for forming the rim of the bowl but on account of its peculiar construction it is necessary to modify the apparatus and to some extent change the method. This modification is necessary, first, because the rim is of channel cross section, the channel opening inwardly or towards the center

of the rim; second, the inclined ports in the lower flange of the rim also necessitate modification in the form of the mold sections.

As illustrated in Figs. 4 to 6 inclusive, the mold for forming the rim comprises a base section F, a top section G, and a plurality of ring segment sections H which engage a recess in the section F. The segments H are preferably four in number distributed about the rim, each section being limited in length so that it can be drawn out of engagement with the molded rim without interference because of the molded-in ports in the flange of the rim. The abutting ends of the sections are also so inclined that the division plane does not cross the inclined ports, thereby avoiding any roughness or change in form of any of said ports. In cross section, each of the segments H is of a downwardly tapering truncated conical form and fits a corresponding recess I in the section F. The section F is also fashioned to form a recess or mold cavity J adjacent to one side of the segments H which forms the portion B³ of the rim. The flange B⁴ of the rim is formed in a recess K in the side of the segments H and the horizontal flange B' is formed by a recess L in the top section G of the mold. Also the inclined recesses which form the ports D are molded in by angular projections M in the recess K.

All of the parts of the mold above described are formed of porous plaster which will absorb water from the slip, leaving solid clay in the mold cavity. In the method of molding, the segments H are placed in the recesses I in the base section F, after which the top section G is placed on the sections F and H to complete the annular mold cavity, it being understood that these sections have suitable dowels (not shown) for holding the same in fixed registration. The slip is then poured into the mold cavity through a suitable sprue opening (not shown) and after standing for the required length of time to absorb the water the mold is reversed into the position shown in Fig. 5. The section F is then lifted off, this being permitted by the tapering cross sectional form of the segments H, which provides the necessary draft. The sections H are next removed successively. The first section to be removed has its ends H', H² at such an angle to each other and to the angle of the projections M that by carefully moving inward first one end and then the other, said sections will be disengaged from the molded rim and from the other sections H. After the removal of this first section H the other sections may be easily removed by sliding them inward over the section G, thereby disengaging

them from the molded flanges B', B⁴ of the rim. Finally the entire rim may be disengaged from the recess L in the section G.

A rim formed by the method and apparatus above described is of very accurate shape which can be engaged with the molded bowl and integrated therewith in the usual manner of joining clay sections with each other. When thus integrated with the bowl the ports D will all be of uniform central sectional area and uniform in the direction of inclination, being also free from any obstruction which would interfere with the flow of water therethrough. Thus in the completed structure the water which is discharged from the channel E through the ports D will flush equally well all sides of the bowl.

Where the rim is applied to a bowl which has a flushing tank integral therewith, portions of this flushing tank may be cast integral with the rim, as indicated at N and O, Fig. 6.

What I claim as my invention is:

1. A mold for casting channeled flushing rims for water closet bowls comprising a plurality of segmental mold sections for molding the undercut portions on opposite sides of said rim, a pair of matched mold sections for molding the external surface of said rim, one of said sections being recessed to receive said segmental mold sections with draft permitting of separation therefrom, and the other of said matched mold sections forming a support for said segmental sections permitting of the lateral withdrawal of the same when said first matched section is removed.

2. A mold for casting channeled flushing rims for water closet bowls comprising a plurality of segmental mold sections together forming an annulus and fashioned to mold the undercut portions of said rim, including a flange for contacting with the inner face of the bowl and with a series of spaced recesses in said flange, and a pair of matched recessed mold sections forming the mold cavity and defining the external surface of the rim, one of said sections being further recessed to receive said segmental mold sections to hold the same in fixed relation and providing draft for removal therefrom, and the other of said matched mold sections forming a support for said segmental mold sections on which they may be laterally withdrawn from the molded rim after disengagement of said first matched mold sections.

3. A mold for casting channeled flushing rims for water closet bowls comprising a plurality of segmental mold sections together forming an annulus and fashioned to mold the undercut portions of said channeled rim including a flange for contacting with the inner face of the bowl, and a series of spaced inclined portions for molding recesses in said flange, the plane of separation between the abutting ends of said segmental sections being inclined to correspond with the inclination of the recess forming portions and arranged intermediate the same to avoid interference therewith, and a pair of matched recessed mold sections for forming the mold cavity and defining the external surface of the rim, one of said matched sections being further recessed to receive said segmental sections and to hold the same in fixed relation, being provided with draft to permit of disengagement therefrom, and the other of said matched sections forming a support on which said segmental sections may be laterally withdrawn from engagement with the molded rim.

4. A mold for casting channeled flushing rims for water closet bowls comprising a plurality of segmental mold sections together forming an annulus and fashioned to mold the undercut portions of said channeled rim including a flange for contacting with the inner face of the bowl, and a series of spaced inclined portions for molding recesses in said flange, the plane of separation between the abutting ends of said segmental sections being inclined to correspond with the inclination of the recess forming portions and arranged intermediate the same to avoid interference therewith, and a pair of matched recessed mold sections for forming the mold cavity and defining the external surface of the rim, one of said matched sections being further recessed to receive said segmental sections and to hold the same in fixed relation, being provided with draft to permit of disengagement therefrom, and the other of said matched sections forming a support on which said segmental sections may be laterally withdrawn from engagement with the molded rim, the inclination of the opposite ends of one of said segmental mold sections being sufficiently divergent to permit of withdrawal of the same in advance and without disturbance of the other segmental sections.

JAMES M. TEAHEN.
